UNITED STATES PATENT OFFICE.

CARL TRAVERS, OF FRANKENHOLZ, NEAR MITTELBEXBACH, GERMANY.

RESPIRATOR.

1,221,246.

Specification of Letters Patent.

Patented Apr. 3, 1917.

Application filed July 16, 1914. Serial No. 851,333.

To all whom it may concern:

Be it known that I, CARL TRAVERS, manager, a resident of Frankenholz, near Mittelbexbach, Palatinate, German Empire, have 5 invented certain new and useful Improvements in Respirators, of which the following is a specification.

This invention relates to respirators and pertains particularly to respirators of novel 10 construction which effectively prevent dust, smoke, disagreeable odors and injurious gases from passing into the lungs. In addition to this main object care has been taken to make the novel respirator compendious 15 and of little weight and of such a shape as to allow of carrying it easily and securely during use. Another object of my invention is to produce a respirator which is adapted 20 for theapeutic purposes and for use by physicians, sick room and hospital attendants.

Heretofore respirators have been constructed in which the air to be purified was passed through a filtering medium such as 25 cotton, spongy and fibrous material, pulverized charcoal and the like. Sometimes the air was conducted through a number of nets, arranged at a certain distance from each other or superposed partitions were employed 30 with moist fabric so arranged as to form a long passage through which the air passed in a zig-zag line for retaining the dust.

The described devices suffer from various 35 defects. A filtering medium prevents easy breathing and a long passage is undesirable for obvious reasons.

The present invention has for its special purpose to overcome the described defects. 40 This has been primarily attained by using walls or partitions within the respirator having rough and moist surfaces provided with a plurality of fine openings so arranged that the partitions are but a small distance from 45 each other. The openings are staggered so that the air, when passing through the respirator, must impinge upon the rough and moist surfaces of the partitions located opposite the said openings. The free passages 50 formed between the partitions are very short whereby any undue resistance is avoided. For ordinary purposes water may be used for wetting the rough surfaces of the inner mechanism because dust and the like adheres 55 and sticks to the moist surfaces. However if the respirator is to be worn in places where

injurious or poisonous gases arise, such as for instance ammonia vapors or acid fumes, then suitable liquids are used for wetting the inner rough surfaces according to requirement. The inrushing air passing through a plurality of openings is divided into a plurality of fine streams which facilitate its purification before being inhaled.

In order to render the invention entirely 65 clear reference is had to the accompanying drawing in which:

Figure 1 represents in longitudinal vertical section a respirator embodying in desirable form the present improvements. 70

Fig. 2 shows the device in elevation.

Fig. 3 is a top plan view of the respirator.

Fig. 4 illustrates in elevation a detail part of the device.

Similar characters of reference denote like 75 parts in all the figures.

In the drawing *a* represents a flat, slightly curved receptacle which may be made of sheet metal or other suitable light material. This receptacle is purposed to be put on the 80 upper lip and worn there when the respirator is in use. The bottom *b* of the receptacle is hinged as shown at *c* to permit of opening the device and a snap lock *d* at the opposite side secures the bottom to the respirator. 85

According to the present invention the receptacle houses a plurality of partitions *e* which are connected to each other. To render the surfaces of these partitions adapted 90 to be wetted or soaked they are covered with textile fabric *f* or other absorbing material. Fine openings *e*, *f* are provided within the partitions which openings are staggered. The distance between the partitions is very 95 small, as may be seen from Figs. 1 and 4.

Practice has proven that the inrushing air, while passing through the apparatus, is perfectly purified and excellent for breathing. As shown in Figs. 1 and 4 the air passages *g*, formed between the partitions are rather 100 small therefore the purification of the air is less effected while passing along these passages than by the quick and easy flow of the air through the openings *e*, *f*.

The top wall *a* of the receptacle *a* is provided with small tubings *a* each intended to be connected with a short tube *h* of rubber or any other suitable material. At the end of each tube a small oval end piece *h* is formed for the nostrils. These end pieces 110 may be provided near their ends each with a circular groove *h*, into which a woolen

thread or an elastic ring or the like may be inserted to form a soft and air-tight closure between the end piece and the nostril walls, which can easily be removed and substituted.

The base piece *b* is provided with a short hollow cylindrical neck *b*¹, closed by a cylindrical filter sack *i* composed of fabric or the like. A ribbon or band is employed for fixing the apparatus in position for use and this band is attached to the receptacle by suitable means such as projections or press buttons, preferably on the side next the face of the wearer.

15 When the device is to be used the frame *e* covered as shown, is dipped in water or other suitable liquid which is absorbed by the covering *f*. The frame is then placed in position within the receptacle *a* by opening the base *b* and then the snap lock *d* is closed. The apparatus is now fixed to the head of the wearer with the nipples *h*¹ placed into the nostrils. The coarse particles contained in the air are held back by the filter *i* through which the air must flow first. The air entering the inner space of the receptacle *a* is divided into a plurality of fine streams passing the openings *f*¹ and *e*¹ and then impinging upon the opposite wall of the cover *f* is purified. The purified air passes then through the nipples *h*¹ and is inhaled.

It may be observed that the frame must be inserted air tight into the walls of the receptacle to prevent the air from passing directly to the nipples *h*¹.

The exhaled air passes from the lungs out over the same course of the apparatus. No special passages and non-return valves or other means are required as is necessary in other known apparatus serving the same purpose.

By virtue of the present construction of the respirator the path for the air to be purified has become very short, which presents a great advantage, namely to easily breathe out the air over the same path over which it is drawn in. In order to facilitate the discharge of the vitiated air from the nostrils into the apparatus there are provided deflecting members such as blades *a*² causing the discharging air to flow laterally toward and into the holes *f*¹ and *e*¹.

There are, as it may be easily understood, a great number of constructions and modifications of the apparatus suitable for carrying the hereinbefore described method into effect: for instance, the base may be provided with side walls, thus forming a separate casing, and put over the casing *a*; in this case the holders may be fastened to the said side walls. There may be used two or even more receptacles instead of only one. Various covering materials may be used for instance wool, flannel, cellulose, porous material as natural or artificial sponge

or the like. Of course the cover *f* may also be arranged on both sides of the metal strips *e*, and it would be no departure from the scope of my invention if a separate path for the expired air breathed out were used.

What I claim is:

1. A respirator with short path for the inrushing and exhaled air comprising a receptacle, a plurality of parallel partitions 75 tight within the receptacle in close proximity to each other and provided with rough, moist surfaces and a plurality of staggered openings, a fabric filter at the bottom of the receptacle, and nostril nipples arranged 80 at the top of the same.

2. A respirator with short path for the inrushing and exhaled air comprising a receptacle, a plurality of parallel partitions tight within the receptacle in close proximity to each other and provided with fabric covered rough, moist surfaces and a plurality of staggered openings, a neck at the bottom of the receptacle, a fabric filter on the said neck, and movable nostril pieces at 85 90 the top of the receptacle.

3. A respirator with one short path for both the inrushing and exhaled air comprising a receptacle, a plurality of parallel partitions tight within the receptacle in close 95 proximity to each other and provided with rough, moist surfaces and a plurality of staggered openings, a fabric filter at the bottom of the receptacle, and nostril nipples arranged at the top of the same.

4. A respirator with one short path for both the inrushing and exhaled air comprising a receptacle, a plurality of parallel partitions tight within the receptacle in close proximity to each other and provided with fabric covered, rough, moist surfaces and a plurality of staggered openings, a neck at the bottom of the receptacle, a fabric filter on the said neck, and movable nostril nipples arranged at the top of the receptacle.

5. A respirator with short path for the inrushing and exhaled air comprising a receptacle curved to fit the upper lip of the user, a hinged bottom portion on the receptacle, an air inlet thereon, a removable frame tight within the receptacle and composed of a plurality of partitions in close proximity to each other and provided with rough, moist surfaces and a plurality of 115 small staggered openings thus forcing the inrushing air to impinge upon the moist surfaces of the frame, and two nostril nipples with flexible connections at the top of the receptacle for inhaling the purified and 120 125 exhaling the vitiated air.

6. A respirator with one short path for both the inrushing and exhaled air comprising a curved receptacle, a removable frame tight therein, composed of a plurality of 130

parallel partitions in close proximity to each other and provided with rough, moist surfaces and a plurality of staggered openings, an air inlet at the bottom of the receptacle, 5 two nostril pieces at its top, and air deflecting plates within, below the said pieces, for deflecting the vitiated air.

In witness whereof I have hereunto set my hand in the presence of two witnesses.

CARL TRAVERS.
